(57) **CLAIM**

The ornamental design for a double lamp holder with ground fault circuit interrupter receptacle, as shown and described.

DESCRIPTION

FIG. 1 is a top perspective view of a double lamp holder with ground fault circuit interrupter receptacle, showing our new design;

FIG. 2 is a top plan view thereof;

FIG. 3 is a front elevation view thereof, a rear view being a mirror image of thereof;

FIG. 4 is a left side elevation view thereof, a right side view being a mirror image of thereof; and,

FIG. 5 is a bottom plan view thereof.
